INVENTOR,

Lucian Bernhard
BY Clousins
ATTORNEY

UNITED STATES PATENT OFFICE.

LUCIAN BERNHARD, OF NEW YORK, N. Y.

DESIGN FOR A TABLE.

Application filed May 6, 1927. Serial No. 21,876. Term of patent 14 years.

To all whom it may concern:

Be it known that I, LUCIAN BERNHARD, a citizen of Germany, residing at New York, in the county of New York and the State of New York, have invented a new, original, and ornamental Design for a Table, of which the following is a specification, reference being had to the accompanying drawing, forming part hereof.

I claim:

The ornamental design for a table as shown.

LUCIAN BERNHARD.
